His Attorney.

UNITED STATES PATENT OFFICE.

GIUSEPPE FACCIOLO, OF PITTSFIELD, MASSACHUSETTS, ASSIGNOR TO GENERAL ELECTRIC COMPANY, A CORPORATION OF NEW YORK.

ELECTRICAL DISTRIBUTING SYSTEM.

1,401,682.

Specification of Letters Patent. Patented Dec. 27, 1921.

Application filed November 26, 1920. Serial No. 426,360.

To all whom it may concern:

Be it known that I, GIUSEPPE FACCIOLO, a citizen of the United States, residing at Pittsfield, in the county of Berkshire, State 5 of Massachusetts, have invented certain new and useful Improvements in Electrical Distributing Systems, of which the following is a specification.

My invention relates to electrical distributing systems, and has for its object an improved arrangement of parts for controlling the same.

More particularly my invention relates to three-wire systems supplying distributing 15 transformers, and provides improved connections therefor, by which the loads on the distributing transformers may be selected by a simple switching operation at the central station.

Where distributing transformers on three-wire systems have a variety of loads thereon, as where there is a lighting load and a power load, it may occur that approximately maximum values of both loads are thrown on the 20 system at substantially the same time. By reason of the different natures of the loads it is generally assumed that maximum values of the two loads will not occur simultaneously, but the experience of central station 25 operators is that two such loads invariably overlap in the course of the day's run and during such overlapping period, or period of the so-called peak load, the supply system and its transformers may easily become over-loaded.

By my invention this occurrence is made impossible for I employ a novel arrangement of the transformers and connections which enables the central station operator or load 30 despatcher to select at will by a simple switching operation, which load is to be supplied with power.

For a more complete understanding of the nature and objects of my invention reference should be had to the following detailed 40 description taken in connection with the accompanying drawing, in which:

Figure 1 shows in diagrammatic fashion an electrical distributing system provided 45 with my invention; Fig. 2 shows the same system in which the central station switch has been shifted to cut out one of the loads; Fig. 3 shows in similar fashion a system embodying a modified arrangement of parts,

while Figs. 4, 5 and 6 show portions of such 55 a system.

Referring now to the drawings, A and B represent the windings on the secondary or supply side of two main transformers, here assumed to be at the central station. The 60 windings A and B supply the three feeders 10, 11 and 12 with electrical energy across which are connected the primaries P_1 and P_2 of two distributing transformers whose secondaries S_1 and S_2 supply the loads on the 65 system. The two primaries P_1 and P_2 are connected so as to have the feeder 11 in common, the secondaries being similarly connected to their loads through the distributing wires 20, 21 and 22. The loads on the secondaries are indicated as of two kinds, a power load being shown at 25 and lighting loads at 26 and 26' respectively.

The power load 25 as shown in Fig. 1 is 70 shown as a pure resistance and is connected across the two secondaries S_1 and S_2 in series without connection to the common return wire 21. The power load indicated at 25, however, need not be a pure resistance but 75 may be any load presumably having characteristics as to constancy, duration and time of demand which differ from the characteristics of the lighting loads at 26 and 26'. Such loads may be series lighting loads, as indicated at 25' in Fig. 5, or motor loads, as are 80 indicated at 25'' in Fig. 6.

The lighting loads 26 and 26' are individually connected across the secondaries S_1 and S_2 , the load 26 being connected to wires 20 and 21 to be across secondary S_1 , while load 90 26' is connected to wires 21 and 22 to be across secondary S_2 .

The switching device for cutting out at will, what in the instance illustrated is the power load 25, comprises a reversing switch 95 for changing the polarity of one of the main transformers with respect to the feeders at 10, 11 and 12. A two-throw reversing switch K is connected across feeders 11 and 12 and has its poles 30, 31 and 32 connected to the 100 terminals of the supply winding of the main transformer B. The pole 30 is electrically connected to pole 31 so that in one position of switch K pole 31 is connected to feeder 11 and pole 32 to feeder 12 while in the other 105 position pole 32 is connected to feeder 11 and pole 30 (or its equivalent pole 31) to feeder 12. This latter position of the switch

K is shown in Fig. 2, the former being shown in Fig. 1.

In Fig. 1 the polarities of the main transformer windings are indicated by the arrows 5 *a* and *b* which impose corresponding polarities in the same direction on the primaries P_1 and P_2 which are indicated by the arrows *c* and *d* as in series. In this position it is therefore seen that there is an E. M. F. to 10 supply current to each of the loads 26 and 26' and an E. M. F. of substantially twice the magnitude of that across the lighting loads to supply current to the power load.

Should the load despatcher at the central 15 station at some time determine that the combined loads at 25, 26 and 26' exceed the desired maximum, or for any other reason, he may cut out the power load by throwing switch K from the position indicated in Fig. 20 1 to the position indicated in Fig. 2.

In the position shown in Fig. 2, the main transformer at B now has reversed polarity with respect to the feeders 11 and 12 so that the polarity of primary winding P_2 is reversed, as indicated by the arrow *d* which is 25 reversed with respect to arrow *c*. It is thus seen that in this second position of switch K the E. M. F.'s of the supply transformers are bucking so that while there is an E. M. F. 30 acting across each load 26 and 26' to supply them with current, the resultant E. M. F. from the series connection of the transformers across the power load is zero; hence no current will flow to the power load.

35 This same effect, however, may be had from a switching device other than a double throw switch. A device for effecting the connections shown in Fig. 3 will also produce bucking E. M. F.'s in the supply transformers. In Fig. 3, the connections are 40 changed from the series arrangement of Fig. 1 to one in which the main transformers A and B are in multiple and the feeder 12 connected to feeder 10. Then since the 45 supply transformers are in multiple the lighting loads 26 and 26' will have E. M. F. across the same to supply current thereto but the load at 25 which is across the secondaries of the supply transformers in series 50 has a zero resultant E. M. F. thereacross. This latter arrangement has the obvious advantage that the lighting loads at 26 and 26' need not be balanced in order to distribute themselves in an economical manner 55 across the transformers A and B, because the two loads are in multiple which are supplied by the transformers A and B which are themselves also in multiple by this connection.

60 Having now described an embodiment of my invention which is at present the best means known to me for carrying the same into effect, I would have it understood that this is merely illustrative and that I do not 65 mean to be limited thereby to the precise

details shown, nor restricted in the choice of recognized equivalents except as defined in my claims hereunto annexed.

What I claim as new and desire to secure by Letters Patent of the United States, is:— 70

1. In an electrical distributing system, the combination with a plurality of main transformers, of a plurality of supply transformers fed therefrom and having a feeder in common, a plurality of loads having 75 different characteristics connected across the supply transformers individually and in series respectively, and a switching device for changing the polarity of a main transformer with respect to its feeders whereby 80 a zero resultant E. M. F. may be had from the series connection of said supply transformers.

2. In an electrical distributing system, the combination with a plurality of main 85 transformers, of a plurality of supply transformers fed therefrom and having a feeder in common, a plurality of loads having different characteristics connected across the supply transformers individually and in 90 series respectively, and a double-throw switch for changing the polarity of a main transformer with respect to its feeders whereby 95 a zero resultant E. M. F. is impressed across the load on the series connection of said supply transformers.

3. In an electrical distributing system, the combination with two main transformers, of two supply transformers fed therefrom and having one feeder in common, loads connected across the supply transformers individually, another load having a characteristic different from the first, said load connected across said supply transformers in series, and a switching device for reversing 100 the polarity of a main transformer with respect to its feeders whereby the E. M. F.'s of the supply transformers across the second named load may be in series or bucking relation. 110

4. In an electrical distributing system, the combination with two main transformers, of two supply transformers fed therefrom and having one feeder in common, loads connected across the supply transformers individually, another load having a characteristic different from the first said load connected across said supply transformers in series, and a double throw switch 115 for reversing the polarity of a main transformer with respect to its feeders. 120

5. In an electrical distributing system, the combination with a plurality of main sources of current, of a plurality of loads connected across the sources of current individually and in series respectively and having a feeder in common, and a switching device for changing the polarity of a main source of current with respect to its feeders, whereby a zero resultant E. M. F. may 130

be had from the series connection of said loads.

6. In an electrical distributing system, the combination with two main sources of current, of two loads connected across the

sources of current individually and having one feeder in common, another load connected across the sources of current in series,

and a switching device for changing the polarity of one of the sources of current with respect to its feeders, whereby a zero resultant E. M. F. may be had from the series connection of said loads.

In witness whereof, I have hereunto set my hand this 22 day of November, 1920.

GIUSEPPE FACCIOLE.
